US0D1063784S

(12) **United States Design Patent** (10) **Patent No.:** **US D1,063,784 S**
(45) **Date of Patent:** **** Feb. 25, 2025**

(54) **TRUCK BODY**

(71) Applicant: **Austin Engineering Limited**, Kewdale
(AU)

(72) Inventors: **Jamie Vincent Clarke Hall**,
Kalamunda (AU); **Deon Wessels**,
Landsdale (AU)

(73) Assignee: **Austin Engineering Limited** (AU)

(**) Term: **15 Years**

(21) Appl. No.: **29/870,745**

(22) Filed: **Feb. 3, 2023**

(51) **LOC (15) Cl.** **12-16**

(52) **U.S. Cl.** **D12/221**
USPC **D12/221**

(58) **Field of Classification Search**

USPC D12/221, 9, 14, 15, 98, 82, 96; D21/431,

D21/434; D15/10, 21-26, 28, 33

CPC B60J 5/00; B60R 7/04

(57) **CLAIM**

The ornamental design for a truck body, as shown and described.

DESCRIPTION

FIG. 1 is an upper perspective view of a truck body, showing our new design;

FIG. 2 is a lower perspective view of the truck body of FIG. 1;

FIG. 3 is a front view of the truck body of FIG. 1;

FIG. 4 is a rear view of the truck body of FIG. 1;

FIG. 5 is a side view of the truck body of FIG. 1;

FIG. 6 is another side view of the truck body of FIG. 1;

FIG. 7 is a top plan view of the truck body of FIG. 1; and,

FIG. 8 is a bottom plan view of the truck body of FIG. 1. The broken lines of even length depict portions of the truck body that form no part of the claimed design.

1 Claim, 8 Drawing Sheets
